United States Patent Office

Des. 193,794

Patented Oct. 9, 1962

193,794

COMBINED STORAGE AND DISPENSING CONTAINER FOR BREAD OR THE LIKE

Nelson Bullock, 522 Adams Ave., Evansville, Ind.

Filed Dec. 9, 1960, Ser. No. 63,174

Term of patent 14 years

(Cl. D44—6)

FIG. 1

FIG. 4

FIG. 5

FIG. 6

FIG. 1 is a side elevational view of a combined storage and dispensing container for bread or the like showing my new design;

FIG. 2 is a left end elevational view;

FIG. 3 is a right end elevational view;

FIG. 4 is a top plan view;

FIG. 5 is a sectional view on line 5—5 of FIG. 4; and,

FIG. 6 is a partial sectional view on line 6—6 of FIG. 4.

I claim:

The ornamental design for a combined storage and dispensing container for bread or the like, as shown.
